UNITED STATES PATENT OFFICE

167,980

LADY'S BOOT

Betty A. Hausfeld, Loveland, and Charles G. Tooker, Cincinnati, Ohio, assignors to So-Lo Works Incorporated, Loveland, Ohio, a corporation of Ohio

Application June 3, 1952, Serial No. 20,016

Term of patent 7 years

(Cl. D7—4)

To all whom it may concern:

Be it known that I, Betty A. Hausfeld, a citizen of the United States, residing at Loveland, in the county of Clermont and State of Ohio, and Charles G. Tooker, a citizen of the United States, residing at Cincinnati, in the county of Hamilton and State of Ohio, have invented a new, original, and ornamental Design for a Lady's Boot, of which the following is a specification, reference being had to the accompanying drawing, forming a part thereof.

The figure is a side elevational view of the lady's boot, showing our new design, the opposite side thereof being plain.

We claim:

The ornamental design for a lady's boot, substantially as shown and described.

BETTY A. HAUSFELD.
CHARLES G. TOOKER.
